HOLDER FOR GOLF TEES AND MARKER

Peter Mondy, 137 Naomi, Arcadia, Calif. 91006

Filed Aug. 31, 1970, Ser. No. 24,781

Term of patent 14 years

Int. Cl. D21—02

U.S. Cl. D34—5

FIG. 1 is a front elevational view of a holder for golf tees and marker showing my new design;

FIG. 2 is a top plan view thereof;

FIG. 3 is a rear elevation thereof;

FIG. 4 is a bottom plan view thereof; and

FIG. 5 is an end view taken at line 5—5 of FIG. 1.

I claim:

The ornamental design for a holder for golf tees and marker, as shown.
